UNITED STATES PATENT OFFICE

2,602,197

STRAIGHTENING DEVICE

Harry H. Schaefer, Cheyenne, Wyo.

Application November 4, 1949, Serial No. 125,632

1 Claim. (Cl. 20—16)

1

This invention relates to a novel straightening device of extremely simple construction adapted to be used for straightening hinged closures including doors, screen doors, window frames and cabinet doors.

Doors and hinged closures of various types frequently warp along the hinged stile between the hinges or beyond the hinges, so that portions of the hinged stile are bowed outwardly and in a direction away from the hinges. When this occurs it is difficult if not impossible to close the door and where the door may be closed the edge of the hinged stile scrapes the face of the hinge jamb of the closure frame and/or binds with a molding strip fastened to the face of the hinge jamb of the frame.

Accordingly, it is a primary object of the present invention to provide a closure straightener of extremely simple construction which may be temporarily secured to the hinge jamb of the closure frame so as to project from the face thereof and be positioned to engage the corner of one face and the edge of the hinged stile of the door and which is located remote to the door hinges for displacing said stile portion toward the door hinges by a camming action as the door approaches a fully closed position to thereby straighten the warp in the door.

Still another object of the invention is to provide a door straightener of extremely simple construction which may be readily applied to or removed from the hinge jamb of a door frame and which may be left in place until the warped condition of a door has been eliminated and thereafter removed.

Various other objects and advantages of the invention will hereinafter become more fully apparent from the following description of the drawing, illustrating a presently preferred embodiment thereof, and wherein:

Figure 1 is a fragmentary side elevational view looking toward the inner face of a portion of the hinge jamb of a door frame, showing the straightening device applied thereto;

Figure 2 is a horizontal sectional view taken substantially along a plane as indicated by the line 2—2 of Figure 1 and showing a portion of the hinged stile of a door in an ajar position, and

Figure 3 is a vertical sectional view taken substantially along a plane as indicated by the line 3—3 of Figure 1 and showing the door straightener in side elevation.

Referring more specifically to the drawing, the door straightener, comprising the invention, is designated generally 5 and comprises a metal bar,

2

designated generally 6 which is bent intermediate of its longitudinal edges and from end-to-end thereof substantially along a line as indicated by the reference numeral 7 to form the surfaces 8 and 9 which are disposed at an obtuse angle to one another greater than 150°. The longitudinal edge 10 of the bar 6, which constitutes the outer edge of the portion providing the surface 8, is provided with a plurality of longitudinally spaced integral projections which project laterally from said edge 10 and which form prongs 11. The prongs 11 are substantially V-shaped having outwardly converging side edges and the opposite sides of the prongs 11 are also tapered adjacent the free ends of the prongs to form the sharpened points 12, as illustrated in Figures 2 and 3.

A portion of the hinge jambs of a closure frame is illustrated in the drawing and designated generally 13 having an inner face 14 which is shown provided with the usual molding strip 15. In Figure 2 a portion of the hinged stile of a door or other closure is illustrated and designated generally 16 and one hinge 17 is shown by which the stile 16 is connected to the jamb 13. However, it will be obvious that at least one additional hinge, not shown, will be provided. Figure 2 is a sectional view taken at a point remote to the hinges of the closure of which the stile 16 forms a part and the stile portion 16 along the section line 2—2 is shown warped and bowed in a direction away from the hinge 17 so that the door or closure could not be closed at the corner 18 of the stile, remote to the hinge 17 will strike the strip 15 or the opposite, inner corner will strike the inner face of the jamb 13 to prevent proper closing of the door. This bowed or warped condition of the corner edge 18 is illustrated in broken lines in Figure 1 and somewhat exaggerated. In order to eliminate this warped condition of the stile 16 between the closure hinges, the prongs 11 of the straightening device 5 are driven into the inner face 14 of the jamb 13 by striking the opposite outer edge of the strip 6 with a hammer or other impact tool and so as to position the other, inner edge 10 of the strip 6 against the face 14 and longitudinally thereof. If the face 14 is provided with a strip 15, as illustrated in the drawing, the side of the strip 6, opposite the surface 8 will be disposed against the edge thereof which normally engages the closure stile 16 and so that the cam surface 9 will extend in a direction away from the stile 16 and from its hinge 17. With the straightening device 6 thus applied, as the closure is swung toward a closed position the corner edge 18 of its hinge stile 16 will contact the cam sur-

face 9 and as the stile 16 continues to move toward the jamb face 14 from its position of Figure 2, the portion of the stile 16, adjacent its corner portion 18 which contacts the surface 9, will be sprung inwardly and away from the straightener 5 so that the door stile 16 will be straightened as the closure reaches a fully closed position and with the stile edge 19 abutting the jamb face 14 and with a portion of the outer surface 20 of the stile 16 being disposed against the straightener surface 8, which is located at a right angle to the jamb face 14. The door straightener 5 may be left in position for a period of time and while the closure is in use until the warp in the stile 16 has been corrected, after which the straightening device 5 may be removed.

Obviously, the straightener device 5 may be made of any desired length and may be provided with any desired and necessary number of prongs 11 and may be formed of any suitable metal which is sufficiently rigid to withstand the pressure required to effect the straightening of the door stile. It will also be readily apparent that the door straightener 5 may be located beyond either end hinge of a closure to function in the same manner and for the same purpose and may be utilized with door jambs not provided with a molding strip 15. Likewise, if necessary, the straightener 5 may be secured to the strip 15 adjacent the edge thereof which is normally engaged by the closure stile and so that the surface 8 will be disposed in the same plane as said edge of the strip 15. The straightener 5 is likewise capable of being utilized in other locations in connection with a closure and a closure frame and may be employed for straightening an end rail of a sliding closure.

Various modifications and changes are contemplated and may obviously be resorted to, without departing from the spirit or scope of the invention as hereinafter defined by the appended claim.

I claim as my invention:

The combination with a closure, a closure jamb and hinges connecting the closure to the closure jamb, of an elongated thick rigid bar having side edge portions disposed at an obtuse angle to one another greater than 150°, a plurality of anchoring elements projecting transversely from one longitudinal edge of said bar and disposed in the same plane as the adjacent side edge portion of the bar, said anchoring elements being anchored in the inner face of the jamb for positioning the side edge portion of the bar, located adjacent said elements, at substantially a right angle to the jamb face, said other side edge portion of the bar having an outer surface disposed at an obtuse angle greater than 150° to the outer surface of the first mentioned side edge portion of the bar and forming a cam surface to be engaged by an edge of the closure as said edge approaches the jamb for displacing said edge of the closure laterally of the jamb, said bar being disposed longitudinally of the jamb and closure and in longitudinally spaced relationship to each of the hinges to cooperate with the hinges, jamb and closure for straightening the closure portion located between the hinges.

HARRY H. SCHAEFER.
